UNITED STATES PATENT OFFICE.

JOHN A. RUSSELL, OF ELIZABETH, NEW JERSEY, ASSIGNOR OF TWO-THIRDS
TO GEORGE B. MARTIN AND GEORGE BAKER, BOTH OF SAME PLACE.

AXLE-LUBRICATOR.

SPECIFICATION forming part of Letters Patent No. 247,417, dated September 20, 1881.

Application filed March 16, 1881. (No model.)

To all whom it may concern:

Be it known that I, JOHN A. RUSSELL, residing in the city of Elizabeth, county of Union, and State of New Jersey, have invented certain new and useful Improvements in Wagon-Axle Lubricators, fully described and represented in the following specification and the accompanying drawings, forming a part of the same.

10 My invention relates to an improvement in axle-lubricators as applied to hubs and spokes of wagon-wheels; and it consists in an improved device to prevent the gumming up or closing of the outlet from an oil-cup attached 15 to the hub, and in the combination of the same with the inner end of a hollow spoke, as hereinafter described.

In the drawings, Figure 1 is a longitudinal section of a hub and one spoke of a wagon or 20 carriage wheel, the spoke and hub being fitted with my improvements. Fig. 2 is a transverse section of an oil-receiver and plunger on a larger scale; Fig. 3, an enlarged section of the spoke B across the receiver r; and Fig. 4, a plan of 25 the plunger detached from the receiver to show the notches p' in its sides.

A is the hub; a, the axle-box; B, the hollow spoke; B', one of the ordinary wooden spokes.

C is the axle, and c c holes formed in the 30 axle-box at its side to admit oil from the receivers r, the latter being shown detached from the spoke at the left end of the hub, as well as formed in the tenon of the hollow spoke shown in Fig. 1. When detached the receiver 35 is formed as a cylindrical vessel, having a screw-cap, s, at one end to admit the charge of oil, and formed with a conical nozzle, n, at the other, through which the oil is discharged.

A plunger, p, is fitted inside the receiver, 40 and consists of a loose plug adapted to slide from one end of the receiver to the other with each revolution of the wheel.

Notches p' are formed in the sides of the 45 plug to permit the passage of the oil freely; and a plunger-rod or pin, b, is secured into its lower end and works through the nozzle n at each stroke of the plunger, carrying a small quantity of oil with it, and effectually preventing the gumming up of the oil-passage by its 50 constant movement.

The receiver when detached from the spoke is sunk into an auger-hole bored into the hub from the outside toward the axle-box a; and the hole c being provided in the box beneath 55 it, the rod b is constructed to pass through the hole, and to drop its charge of oil directly upon the axle C.

A rib, e, is provided upon the side of the receiver to cut into the wood and keep the metal 60 cylinder from turning. When formed in the hollow spoke the receiver consists of a cylindrical or other shaped tube provided in that part of the spoke inserted in the hub, and fitted with a screw-nozzle, n', through which 65 the rod b reciprocates, as before described, the plunger being arranged in the tube as in the detached receiver, and restricted in its movement by a bridge, d, in the interior of the spoke.

The bridge is provided with a hole, i, communicating with a chamber or hollow, f, formed inside the spoke for the purpose of holding a 70 large supply of oil. Such hollow may extend the whole length of the spoke by making it entirely of metal; or a portion of the spoke may 75 be made of wood, as shown at g in the drawings, by inserting the same into a socket, h, formed in the upper end of the metallic part of the spoke.

For filling the reservoir or chamber f, a hole 80 is provided in the side of the spoke at j, and a screw button or plug, k, is employed to keep it closed.

When the axle-box a is short the oil fed 85 from the receiver in the hollow spoke will suffice to oil the bearing; but for long hubs I connect the reservoir or spoke-receiver with a detached receiver sunk in the wood of the hub, as shown in Fig. 1, through the medium of a small tube or pipe, t, secured by screw-thread 90 or solder into both.

In Figs. 4 and 2 is shown a device for insuring the movement of the plunger p in the receiver r, the same consisting in a loose ball, l, arranged in a tubular hollow, m, formed inside 95 the plunger, and protected from access of oil by a plate, o, soldered air-tight over the hollow m.

As the receiver is carried around the axle 100 by the revolutions of the hub the ball rolls alternately from one end of the hollow m to the

other, and drives the plunger from its previous position by its momentum.

I am aware that it is not new to employ a sliding pin to clean out the oil-hole leading to a wagon-box; but in such inventions as Patents Nos. 207,493, of 1878, and 157,576, of 1874, no provision exists for insuring the movement of the cleansing-pin when the oil is thick or gummy; and my invention is especially intended to obviate the defect inherent in all previous structures by attaching a heavy plunger to the pin and making the latter of very small diameter, so that the momentum of the plunger may readily overcome any resistance encountered in the oil-hole. To further insure the movement of the plunger itself, my invention provides the moving ball, protected from the oil completely by its inclosure in the inside of the plunger, and I thus effectively prevent the sticking of the pin, which frequently occurs with other inventions.

I am aware that a hollow spoke is not new, as it is shown in Bruns's Patent No. 182,555, of 1876; and I therefore disclaim the sliding pin and the hollow spoke, except as combined in the manner which I claim as follows:

1. In a lubricator for wagon-wheels containing a plunger reciprocated by the operation of gravity, the combination of the receiver *r*, having a tapering nozzle, *n*, with the pin *b*, operated by the plunger *p*, formed with notches *p'*, the whole arranged and operating substantially as and for the purpose set forth. 30

2. The combination, with the plunger *p*, of the hollow chamber *m*, and the loose ball *l* secured therein air-tight to secure the exclusion of oil, and operating to move the plunger by its momentum, in the manner herein set forth. 35

3. The combination, in a hollow spoke, of two receivers separated by the bridge *d*, one serving as an oil-reservoir, and the other operating in combination with the plunger *p* and pin *b*, substantially as shown and described. 40

In testimony whereof I have hereunto set my hand in the presence of two subscribing witnesses. 45

JOHN A. RUSSELL.
